TICKET FOLDING DEVICE FOR DEPOSITORY

Clyde T. Ervin, Lebanon, and George A. Jacoby, Hamilton, Ohio, assignors to The Mosler Safe Company, Hamilton, Ohio, a corporation of New York

Application April 13, 1951, Serial No. 220,858

7 Claims. (Cl. 270—61)

This invention relates to a device for folding a receipt ticket and for issuing the ticket. More particularly, it relates to an improvement in a receipt issuing depository of the type disclosed generally in the co-pending application of Jack N. Binns, Thomas E. Dugle, and Alvin F. Alt, Serial No. 121,416, filed October 14, 1949, now U. S. Patent No. 2,572,003, issued October 23, 1951.

The depository of the Binns et al. application issues a receipt ticket which is folded double as it is issued, and the present invention is particularly directed to a machine for folding a ticket as it is issued.

An object of this invention is to provide a device which folds and discharges a receipt ticket through a slot with the fold first.

A further object of this invention is to provide a ticket folding device having a tongue which moves across the path of a ticket as the ticket is advanced to fold and eject the ticket through a slot.

A further object of this invention is to provide a ticket folder having a knife operating in timed relation thereto, to cut off a ticket when a ticket has been folded and issued.

The above and other objects and features of the invention will in part be apparent and will in part be obvious from the following detailed description, and the drawings, in which:

Figure 1 is a view in front elevation showing a depository having ticket folding means constructed in accordance with an embodiment of this invention, the depository being shown mounted in a wall of a building;

Fig. 2 is an enlarged view in section taken along a line II—II of Fig. 1, the ticket folding mechanism being shown in ticket released position;

Fig. 3 is an enlarged view in section taken along the same line as Fig. 2, showing the ticket folding mechanism in ticket engaging position;

Fig. 4 is a perspective view of the ticket folding member;

Fig. 5 is a fragmentary view in side elevation of the depository;

Fig. 6 is a view partly in elevation and partly in section taken along a line VI—VI in Fig. 5;

Fig. 7 is a plan view showing a portion of a strip of tickets of the type utilized in the depository; and

Fig. 8 is a view in section taken along a line VIII—VIII in Fig. 7.

In the following detailed description, and the drawings, like reference characters indicate like parts.

In Figs. 1-3 is shown a front panel 10 of the housing of a depository of the type used by banks and the like for receiving deposits after banking hours and when tellers are not ordinarily available. Panel 10 closes an opening in an appropriate wall 11 of the bank building or other appropriate place and includes a slot 12 through which receipt tickets are issued. As shown in Figs. 2 and 3, a strip of tickets 13 is advanced by a ticket feeding wheel 14 toward the face plate to bring free end 15 of the ticket strip onto a support member 16 (Fig. 2). Support member 16 is mounted immediately above the ticket slot. As free end 15 is fed onto support member 16, an oscillating

2

ticket folding member 17 (Figs. 2-4) is swung from the Fig. 2 position to the Fig. 3 position, engaging and folding the portion of the ticket strip which forms one ticket and ejecting the ticket through the slot 12 with the fold first. As the ticket is ejected, a cut-off knife 17' cuts the ticket from the strip.

The device which has been described in general terms to this point will now be described in greater detail.

In Figs. 7 and 8 is shown a portion of the strip of tickets employed in the machine. The strip of tickets is similar to that employed in the machine of the above mentioned Binns et al. application. Each ticket of the strip is provided with embossed indicia 18. During operation of the mechanism of the depository (not shown in detail), the indicia are inked so that the indicia can be printed on a package deposited in the depository. The ticket strip is provided with a series of spaced holes 19. Holes 19 fit over sprockets 21 (Figs. 2 and 3) of the ticket wheel 14 so that the wheel can advance the tickets. The sides of the ticket strip are notched, as indicated at 22 (Fig. 7), and the strip is cut into tickets by knife 17' at the notched positions. A line of weakening 23 extends across each ticket. Each ticket is folded upon itself along line 23 as it is ejected through the slot so that the inked indicia are covered as each ticket is ejected.

The strip of tickets is advanced by ticket folding wheel 14 (Figs. 2 and 3) across a guide plate 24. Guide plate 24 is slotted at 25 to provide a shearing edge 25' against which the knife cuts the ticket strip. The free end of the ticket strip crosses a narrow opening 26 at the end of guide plate 24 to reach support member 16. Support member 16 forms the lower wall of a hollow housing 27. Housing 27 supports and normally encloses ticket folding member 17. The housing extends outwardly of face plate 10 and has a mouth opening inwardly so that the ticket folding member can swing or oscillate into and out of housing 27. The ticket folding member swings between normal position in which it is entirely housed in housing 27 (Fig. 2) and a ticket engaging position in which ticket folding member 17 extends through opening 26 and slot 12 (Fig. 3).

Ticket folding member 17 (Fig. 4) includes a segmentally curved tongue 28, which engages the ticket, and a pair of spaced pivot carrying arms 29 attached to opposite sides thereof. Arms 29 are pivotally mounted in the housing, as shown in Figs. 2 and 3 on pivots 30 on which the ticket folding member turns.

The ticket folding member turns with a gear 31. Gear 31 is driven by a train of gears including an intermittent gear 32, an idle gear 33, and a spring biased gear 34. Intermittent gear 32 is driven by ticket folding wheel 14. As the strip of tickets is advanced one ticket length, one plane surface and one set of teeth of intermittent gear 32 pass idle gear 33. Thus, idle gear 33 is released for the first portion of the advance of the ticket and is engaged for the remainder of the advance thereof, so that the ticket folding member oscillates into engagement with the ticket when the ticket extends into housing 27.

As shown in Figs. 5 and 6, idle gear 33 and spring biased gear 34 are mounted on one side of a plate 36. Plate 36 extends rearwardly from and is integral with front panel 10. Gear 34 meshes with gears 33 and 31 and is mounted on a shaft 37. Shaft 37 extends through plate 36 and carries a crank arm 38 on the other side of plate 36. Crank arm 38 is urged downwardly, as shown in Fig. 5, by a spring 39 to urge the gears to a position in which the ticket folding member is inside housing 27 so that when one of the plane surfaces of intermittent gear 32 is opposite gear 33, the ticket folding member is in housing 27. Then, when one of the toothed sections of gear 32 engages idle gear 33, the ticket folding member oscillates to bring the tongue thereof against the ticket

to fold the ticket along the line of fold and eject the ticket through slot 12 fold line first. Finally, the cut-off knife drops to cut the ticket from the strip. Then the ticket can be grasped at the fold and pulled from the slot, and there is no danger of touching the inked surfaces of the ticket indicia, for the indicia are inside and covered by the folds of the ticket.

When the cut-off knife has fallen to cut a ticket free, the knife is raised before the ticket feeding wheel 14 is again advanced. The knife is raised by a cam 41. Cam 41 is rotatably mounted on the shaft of ticket feeding wheel 14. When the knife has fallen, cam 41 is swung clockwise, as shown in Figs. 2 and 3, to engage a roller 42. Roller 42 is attached to a knife supporting arm 43 so that when the cam engages roller 42, the knife is raised. Then, when ticket feeding wheel 14 is again advanced, cam 41 advances therewith counterclockwise to the position shown in Fig. 3 at which cam 41 is disengaged from roller 42. As the ticket feeding wheel turns, a cam surface 44 on the wheel engages a lug 46. Lug 46 is mounted on knife supporting arm 43 and holds the knife in elevated position until a notch 47 in cam surface 44 reaches the lug, whereupon the knife falls. As the knife falls, it is pulled downwardly by a spring 48 (only part of which is shown) to cut the ticket from the strip.

Other parts of the structure of the depository, including mechanism for driving the cam and the ticket wheel are shown and claimed in the aforementioned co-pending application of Jack N. Binns et al.

The ticket folding device of this invention engages and folds each ticket as the ticket is advanced toward the face plate. Each ticket is engaged by the tongue of ticket folding member 17 and ejected positively thereby.

The ticket folding device described above and illustrated in the drawings is subject to structural modification without departing from the spirit and scope of the appended claims.

Having described our invention, what we claim as new and desire to secure by Letters Patent is:

1. A receipt ticket folding and issuing device which comprises a face plate having a ticket slot therein, a ticket support member adjacent and spaced from said slot and extending outwardly of said face plate substantially perpendicularly thereto, means disposed inwardly of said face plate for feeding the free end of a ticket blank through the face plate and onto said support member, an oscillating ticket folding member normally disposed above said support member and disposed to pass out and in said slot to bend the ticket blank onto itself, means operating in timed relation with the ticket feeding means for oscillating the ticket folding member, whereby the tickets are folded one at a time and ejected through the slot fold line first, and means for returning the ticket folding member to normal position when the folded ticket has been advanced through the slot.

2. A receipt ticket folding and issuing device in accordance with claim 1 characterized by the fact that the ticket folding member comprises a segmentally curved ticket folding tongue for engaging the ticket and pivots on the axis of said tongue, said tongue being pivotally mounted on said pivots above the support member and swinging between a released position in which the tongue is above the support member and an operative position in which the tongue extends through the slot.

3. A ticket feeding and issuing device which comprises a face plate having a ticket slot therein, a hollow housing extending outwardly of said plate adjacent said slot, said housing having a mouth opening through the face plate spaced from the slot, means disposed inwardly of said face plate for feeding the free end of a ticket blank through the mouth and into the housing, an oscillating ticket folding member disposed to pass across the path of the ticket and out and in said slot to bend the ticket blank onto itself, and means operating in timed relation with the ticket feeding means for oscillating the ticket folding member having a curved ticket

member, whereby the tickets are folded one at a time and ejected through the slot fold line first.

4. A receipt ticket folding and issuing device which comprises a face plate having a ticket slot therein, a hollow housing extending outwardly of said plate adjacent said slot, said housing having a mouth opening through the face plate spaced from the slot, a rotatable ticket feeding wheel in the device for feeding the free end of a ticket blank through the face plate and into the housing, an oscillating ticket folding member disposed to pass across the path of the ticket and out and in said slot to bend the ticket blank onto itself, a gear drive for advancing the ticket folding member, an intermittent gear connected to the ticket feeding wheel, the teeth of the intermittent gear engaging a gear in said gear drive whereby the ticket folding member is advanced from a normal position into engagement with the ticket as the ticket is advanced into the housing and the ticket is folded and ejected through the slot fold line first, the intermittent gear releasing the gear drive when the folded ticket has been ejected, and means for returning the ticket folding member to normal position.

5. A receipt ticket folding and issuing device which comprises a face plate having a ticket slot therein, a hollow housing extending outwardly of said plate adjacent said slot, said housing having a mouth opening through the face plate spaced from the slot, means in the device for feeding the free end of a ticket blank through the mouth and into the housing, an oscillating ticket folding member pivotally mounted in said housing, said member having a curved ticket engaging tongue and swinging between a ticket engaging position in which the tongue extends through the slot and a released position in which the tongue is housed in the housing, and means operating in timed relation with the ticket feeding means for advancing the ticket folding member to ticket engaging position as the ticket is advanced into said housing to fold and eject the ticket through the slot fold line first, and means for returning the ticket folding member to released position when the folded ticket has been ejected.

6. A receipt ticket folding and issuing device which comprises a face plate having a ticket slot therein, a hollow housing attached to and extending outwardly of said plate adjacent said slot, said housing having an open mouth extending through the face plate spaced from the slot, means in the device for feeding the free end of a ticket from an elongated strip of tickets through the mouth and into the housing, an oscillating ticket folding member pivotally mounted in said housing, said member having a curved ticket engaging tongue and swinging between a ticket engaging position in which the tongue extends through the slot and a released position in which the tongue is housed in the housing, means operating in timed relation with the ticket feeding means for oscillating the ticket folding member to ticket engaged position as the ticket is advanced into said housing, whereby the ticket is folded and ejected through the slot fold line first, means operating in timed relation with the ticket advancing means for cutting the ticket from the strip of tickets when ejected through the slot, and means for returning the ticket folding member to released position when the folded ticket has been ejected.

7. A receipt ticket-folding and issuing device which comprises a face plate having a ticket slot therein, a hollow housing extending outwardly of said face plate in alignment with but spaced from said slot, said housing having a mouth in the face plate in alignment with the slot, a ticket-guiding plate for guiding one end of a ticket blank from inside the face plate toward the face plate and into the mouth of the housing, said ticket-guiding plate being spaced from the face plate, an oscillating ticket-folding member pivotally mounted in said housing, said ticket-folding member having a curved ticket engaging tongue, said tongue swinging between a ticket

engaging position in which the tongue extends through the space between the ticket-guiding plate and the face plate and through the slot and a released position in which the tongue is housed in the housing, means operating in timed relation with the ticket feeding means for advancing the tongue to ticket engaging position as the ticket is advanced into said housing to fold and eject the ticket through the slot fold line first, and means for returning the ticket folding member to released position when the folded ticket has been ejected.
